CLAIM

The ornamental design for a drop-leaf bar cart, as shown and described.

DESCRIPTION

FIG. 1 is a top, end and side perspective view of a drop-leaf bar cart showing my new design, with the drop leaves raised;

FIG. 2 is a side perspective view thereof;

FIG. 3 is an end perspective view thereof;

FIG. 4 is a top plan view thereof;

FIG. 5 is a top, end and side perspective view thereof with the leaves in lowered condition; and

FIG. 6 is an enlarged bottom perspective view thereof.

FIG. 1

FIG. 2

FIG. 3

FIG. 5

FIG. 4

FIG. 6
